Carpets

No. 5,633.

Mar. 5, 1872.

UNITED STATES PATENT OFFICE

JOSEPH JAMES PATCHETT, OF HALIFAX, ENGLAND, ASSIGNOR TO JOSEPH WILD & CO., OF NEW YORK CITY.

DESIGN FOR A CARPET-PATTERN.

Specification forming part of Design No. 5,633, dated March 5, 1872.

Specification describing a Design for Carpets, invented by J. J. PATCHETT, of Halifax, in the county of York, England.

The accompanying photograph fully represents my new design.

This invention relates to a new design for carpets or similar fabrics; and consists, first, in a new design of the main or center figure A, which is of peculiar mixtilinear outline, of which one-quarter is shown in the photograph, and embraces an hexagonal, decorated figure, a, within which a quatrefoil, b, is formed. The invention consists, secondly, in the new design of the smaller figure B, which is somewhat similar in its mixtilinear outline to A. Thirdly, the invention consists in the design of the ornamental oval C, which has beads d d at the ends, and wings e e at the sides, as shown.

Finally, the invention consists of the new ornamental scroll D, which fills the ground between the figures A, B, and C, and is formed as shown.

I claim as my invention—

1. The design of the figure A, as described.
2. The design of the figure B, as described.
3. The design of the figure C, as described.
4. The design of the ornamental scroll D, as described.
5. The design for a carpet, consisting of the combination of the figures A B C and scroll D, as described.

JOSEPH JAMES PATCHETT.
